UNITED STATES PATENT OFFICE.

DEWEY H. BITNEY, OF ALBION, MICHIGAN, ASSIGNOR TO UNION STEEL PRODUCTS COMPANY, OF ALBION, MICHIGAN.

ANCHOR INSERT FOR CONCRETE WORK.

Application filed January 6, 1928. Serial No. 244,863.

The main objects of this invention are to provide an anchor insert for concrete and coacting tie members which is well adapted for use in the walls and ceilings of buildings, the insert being very securely imbedded in the concrete body without materially weakening the same and one with which ties may be quickly engaged in any desired position and the ties are securely retained.

10 Objects relating to details and economies of my invention will appear from the description to follow. The invention is defined and pointed out in the claims.

15 A structure which is a preferred embodiment of my invention is illustrated in the accompanying drawing, forming a part of this application, in which:

20 Fig. 1 is a fragmentary portion of a wall and a wall facing with my improved anchor inserts in operative relation thereto.

25 Fig. 2 is a fragmentary perspective view of a concrete wall or body with one of my improved anchor channel members imbedded therein.

Fig. 3 is a fragmentary perspective view of my improved anchor wall member.

In the drawing similar reference characters refer to similar parts throughout the several views.

30 Referring to the drawing, 1 represents a concrete body such as a wall and 2 the anchor part, such as a brick wall.

35 My improved anchor insert 3 is formed of sheet metal into an L or angled cross section. This is imbedded in the concrete body as the body is poured with the edges 4 of the channel member in flush relation to the face 5 of the body.

40 The member 3 is of such dimensions that a substantial overhang 6 of concrete is secured, thereby very effectively and securely anchoring the insert in the concrete body with a minimum of splitting or fracturing action when stress is applied to the anchor member.

I provide a plurality of tie members 7 having arms 8 at their inner ends which are adapted to be introduced into the channel when presented longitudinally to the slot or entrance thereof, as indicated in Fig. 2.

These tie members, when used for anchoring a facing wall, as 2, have laterally turned outer ends 9.

The tie members are a comparatively close fit in the anchoring channel so that it is 55 quite impossible to withdraw the same by a direct pull on the tie member, the tie members holding securely unless withdrawn by a partially rotative movement to align the arms thereof with the slot or entrance portion of the channel.

If desired, the outer ends of the tie members may be variously shaped according to the work for which they are intended or the part which they are designed to anchor. 65

My improved anchor insert is very simple and economical and is capable of use in a great variety of relations and the ties may be quickly inserted and adjusted to any desired position.

Having thus described my invention, what I claim as new and desire to secure by Letters Patent, is:

1. An anchor for concrete work comprising a channel member of L cross section 75 adapted to be imbedded in a concrete body with its edges flush with the face of the body and its arm portions substantially spaced from the face of the body, and angled tie members adapted to be introduced into 80 said channel member when their arms are presented longitudinally thereto and interlocked therewith by a rotative movement within the channel member, said tie members being freely adjustable longitudinally 85 of said channel members.

2. An anchor for concrete work comprising an elongated channel member of L cross section adapted to be imbedded in a concrete body to open at the surface of the body, and 90 a tie member having a laterally projecting arm adapted to be introduced into said channel member when the arm is presented longitudinally to the channel member and to be engaged therewith by a rotative movement of the tie member.

In witness whereof I have hereunto set my hand.

DEWEY H. BITNEY.
